United States Patent

Des. 241,426
Patented Sept. 14, 1976

241,426

STRUCTURAL COLUMN

Kenneth J. Davis, 529 Brier Road,
Kenilworth, Ill. 60043

Filed Apr. 23, 1975, Ser. No. 570,623

Term of patent 14 years

Int. Cl. D25—01

U.S. Cl. D25—77

FIG. 1 is a perspective view of a structural column showing my new design, with the broken line disclosure of flooring being for illustrative purposes only;

FIG. 2 is an enlarged bottom view thereof;

FIG. 3 is a front elevational view thereof; and
FIG. 4 is a side elevational view thereof.

The bottom and top are flat and unornamented.

I claim:

The ornamental design for a structural column, substantially as shown and described.
